CONTOUR BODY SUPPORT FOR CHAIR CONSTRUCTIONS

Jerome Freedman, Brooklyn, N. Y., and Julius Feldhorn, Glen Ridge, N. J.

Application November 24, 1953, Serial No. 27,780

Term of patent 14 years

(Cl. D15—1)

To all whom it may concern:

Be it known that we, Jerome Freedman and Julius Feldhorn, citizens of the United States, residing respectively at Brooklyn, in the county of Kings, State of New York, and Glen Ridge, in the county of Essex, State of New Jersey, have invented a new, original, and ornamental Design for Contour Body Support for Chair Constructions, of which the following is a specification, reference being had to the accompanying drawing, forming part thereof, in which:

Fig. 1 is a side perspective view of a contour body support for chair constructions, showing in full lines our new design, the broken lines indicating in outline one of the forms of leg structure which may be detachably and interchangeably used to support same; and

Fig. 2 is a bottom view, the broken lines here indicating part of the outline of one of said forms of leg structure.

We claim:

The ornamental design for contour body support for chair constructions, substantially as shown and described.
